[57] **CLAIM**

The ornamental design for an inframammary dissector instrument, substantially as shown and described.

DESCRIPTION

FIG. 1 is a top plan view of the inframammary dissector instrument of my design.

FIG. 2 is a left side elevational view thereof.

FIG. 3 is a front end view thereof.

FIG. 4 is a rear end view thereof.

The bottom plan view (not shown) and the righthand side elevation (not shown) are mirror images of FIGS. 1 and 2, respectively.

FIG. 1

FIG. 2

FIG. 3

FIG. 4
